OF NEW YORK, N. Y.

DEVICE FOR DEVELOPING ROLL-FILMS.

1,212,498.

Specification of Letters Patent. Patented Jan. 16, 1917.

Application filed February 28, 1916. Serial No. 81,251.

To all whom it may concern:

Be it known that I, LE ROY W. KELSBY, a citizen of the United States of America, residing at New York city, New York, have invented certain new and useful Improvements in Devices for Developing Roll-Films, of which the following is a specification.

This invention relates to a device for developing roll films, and has for its object the providing of a construction which will allow a better and quicker development of a film.

Another object in view is to provide a construction whereby the film may be held in a substantially spirally wound condition with the turns of the spiral separate, and thoroughly developed in a comparatively small container.

A still further object in view is to provide a device for receiving a roll film, upon which the film will automatically adjust itself with the layers spaced apart so that the developing and fixing solution may be easily and quickly applied to the sensitive material and it may be easily rinsed to cleanse it when developed and fixed.

Figure 1. is a longitudinal vertical sectional view of one form of my device. Fig. 2. is a sectional view on line 2—2 of Fig. 1 minus the upper part of the disk 2, which was broken away to give space. Fig. 3. is a sectional view on line 3—3 of Fig. 1 minus the upper part of the disk 3, which is broken away to give space. Fig. 4. is a vertical, longitudinal, sectional view of a simple form of parts of my device. Fig. 5. is a perspective view illustrating the method of applying the film upon the holder. Fig. 6. is a perspective view of a developing, fixing and washing machine and associated parts. Fig. 7. is a perspective view showing how the film is being washed after the same has been passed through the fixing bath.

1 indicates the holder as an entirety and 2 and 3 the end members which are preferably thin disks spirally corrugated as at 4 and 5, respectively, as shown in Figs. 2 and 3. In the corrugations 4 is arranged a plurality of rows of apertures 6, while in the corrugations 5 a plurality of rows of apertures 7 is provided. The ends may be made from any suitable material but are preferably pressed from sheet metal. From Fig. 1 it will be observed that the apertures 6 are arranged in that part of the corrugations forming the groove, looking at the end from inside of the

holder, though I do not limit myself to that arrangement.

Arranged centrally of the holder is a tubular member 8 having a slot 9 and a threaded extension 10 which projects through an aperture in end 2 so that the clamping nut 11 may be applied. A centering pin 12 is arranged to engage the end 13 of the tubular member 8, while at the opposite end I provide a centering pin 14 which extends 65 through the end 3 and into the end member 15 of tube 8. The end member 15 has also, threaded therein, the end of a projecting tubular member 16 which acts as a nut for clamping the end 3 in position and also as a 70 tubular inlet member for fluid, hereinafter fully described. The centering pins 12 and 14 are very desirable as the entrance portions 17 and 18 (Figs. 2 and 3) should be opposite each other in order that the end of 75 the film 19 (Fig. 5) may be properly positioned and caused to pass spirally around member 8, the same following the various grooves in the ends 2 and 3. The natural tendency to curl, of the film 19, causes the 80 film to easily follow these grooves by a slight pressure on the film.

Considering the spiral groove of one disk, as that receiving the film, the complementary disk is the means for holding the film in the 85 spiral groove of the disk which is opposite to it, though I do not limit myself to means of that exact form.

In place of the form thus far described, I may use a simple tube, and spirally grooved 90 disks secured thereto as seen in Fig. 4.

After the film has been exposed in the usual manner the same is caused to take its position on the holder 1, as shown in Fig. 5 and in dotted lines in Fig. 1. This may be 95 done by entering the film in the groove, unrolling it to the full length and then feeding it toward the holder. The resilience of the film will cause it to wind itself up in the spiral grooves, and that without touching the holder except on the edges of the film, the inclined walls of the groove preventing any face contact and thus avoiding any injury to the impression on the film.

The disks should be separated just enough 105 to permit the entry of the film, with a clearance sufficient to avoid friction. The holder, together with the film, is then placed in the container 20 which contains a sufficient amount of developing fluid to entirely sub- 110

merge the container. The solution may freely enter the apertures 6 and 7 and thus quickly come in contact with all parts of the sensitive material on the film. After 5 the film has been in the developing solution for the desired length of time it is removed and, if desired, dipped in water so as to remove the remnants of the developing fluid, and then the holder with the film 10 thereon is placed in the second container 21, which contains a fixing solution. After the film has been in the fixing solution for the desired length of time, the same is removed and the fixing solution is also removed 15 by being poured in some other receptacle. The film and the holder are then placed back in the container 21 and the lid 22 is inverted so that the stem 23 may fit over member 16, as shown in Fig. 7, thus 20 providing a funnel. It may then be placed under a faucet and the water is then turned on by opening the spigot 24, whereby clean running water may be continuously supplied to the interior of tube 8 and caused to pass 25 out opening 9 and thence circulate through the various layers of the film. Of course, some of the water escapes out of openings 5 and 6, but there will be a thorough washing in a minimum amount of time of the 30 entire surface of the film. It is to be noted that the developing, fixing and washing are done in a very small space and yet all of the parts of the film are thoroughly acted on in such a manner as to obtain the best results. 35 Moreover, the film need not be touched from the time it is placed in the holder which protects it from damage during the developing, and the fingers need not touch the fluids used, thereby avoiding the staining or 40 poisoning by said fluids.

What I claim is:—

1. In a device of the character described, 45 a holder provided with a spiral groove having inclined walls, for receiving the edge of a film, whereby the film may be wound thereon so that there will be a space between consecutive layers, and means for holding the film in the spiral groove.

2. In a device of the character described, 50 a holder comprising a pair of spaced end members having evenly set spirals thereon for guiding a film as it is wound on the holder, the turns of the spiral being fixedly secured in positions definitely separated by 55 a space wider than the thickness of a film, and means for holding said members in a given position.

3. In a device of the character described, 60 a holder provided with a pair of spaced end members provided with registering spiral grooves having inclined walls and means for holding said ends in a predetermined position.

4. In a device of the character described, 65 a holder provided with a pair of spaced end

members provided with registering spiral grooves having substantially continuous inclined walls, with smooth bottom faces and means for holding said end members in a predetermined position.

5. In a device of the character described, 70 a holder provided with end members as set forth and presenting spiral grooves registering one with the other and adapted to receive the edges of a film, said grooves having the same spiral form, whereby the film may be started in the outer groove and moved so as to be spirally wound, therein, and means for holding said end members spaced a predetermined distance apart.

6. In a device of the character described, 75 a tubular member, provided with an outlet between its ends and an inlet at one end, end members secured to said tubular member, at substantially right angles to its axis, 80 and provided with fixed projections, arranged as described, in form to bound a spiral groove opening into the space into which the outlet from the tubular member leads, all substantially as set forth, whereby 85 said outlet and said groove constitute a fixed continuously open passage from the tubular member to the outer end of the spiral groove.

7. In a device of the character described, 90 a holder comprising end members provided with means for receiving and holding in place, a film wound in a spiral, said end members having apertures arranged therein, and adapted to permit a fluid to pass between the coils of the film, and means for holding the said end members a predetermined distance apart.

8. In a device of the character described, 95 a holder formed with corrugated end members, the corrugations having inclined walls 100 and being arranged in spirals, the spiral of one end being opposite the spiral of the other end whereby there are spiral grooves facing each other adapted to receive the edges of a film whereby it is permitted to 105 pass on and to assume a coiled condition with the layers spaced apart, each of said end members being formed with a plurality of apertures, and means for holding said end members a predetermined distance 110 apart, said means being provided with a passageway therein, adapted to permit the passage of the fluid between said end members within the coiled film.

9. In a device of the character described, 115 a holder provided with end members formed with grooves for receiving the edges of a coiled film, and provided with apertures, a receptacle for receiving said holder, and arranged to contain a solution adapted to 120 act on the film, and passages substantially as set forth whereby said fluid may simultaneously act on all the sensitive matter.

10. In a device of the character described, 125 a holder formed with ends adapted to hold 130

both the edges of a coiling film, a hollow supply member having a projection extending beyond one of said ends, a container for receiving said holder, and a funnel member 5 provided with a body and an extension being adapted to fit the extension on the holder whereby fluid may be guided to a position in said holder and within the coiled film, one side of said funnel member being arranged 10 as set forth to fit the holder extension and the other so that the body will act as a cap for said container.

11. In a device of the character described,

a holder provided with end members and a central body formed with a passageway 15 therethrough, each of said end members being formed with substantially continuous means permanently arranged for receiving the edges of a film and guiding the film as the same is forced on the holder so that 20 the film will be wound spirally and the layers will be spaced apart.

In testimony whereof, I have signed my name to this specification this 26th day of February 1916.

LE ROY W. KELSAY.
